CHARLES ALBERT DUBOIS, OF PARIS, FRANCE, ASSIGNOR TO THE SOCIÉTÉ PARISIENNE
DE MECANIQUE GENERALE, OF PARIS, FRANCE.

TAXIMETER.

Application filed April 5, 1923, Serial No. 630,141, and in France April 15, 1922.

The present invention relates to taximeters and more particularly to a construction for transforming the continuous movements of the mileage or time mechanisms, into an intermittent motion, acting on the usual drums for indicating the tariff.

This intermediate mechanism is characterized by simplicity of structure and the absence of springs or similar devices so that there is small opportunity for the arrangement to become disordered.

The invention is capable of manufacture and application at small cost and provides a safe and accurate medium for accomplishing the purpose intended.

In the drawings, wherein similar reference characters designate corresponding parts throughout the several views:

Figure 1 is a view in section showing the shaft and connected parts rotated during travel, by the distance or time operated devices.

Figures 2 and 3 show the mechanism for converting the slow continuous motion of the shaft into abrupt intermittent motion acting on the tariff drums.

Referring to Figure 1, the numeral 1 indicates a disc having a sleeve 1' integral or secured thereto in any desired manner. The sleeve 1' has at its free end, peripheral teeth engaging in clutching relation the adjacent peripheral teeth of a sleeve 2.

The disc 1 is loosely mounted on a shaft 3 adapted to be rotated selectively by the mileage or time translating mechanisms. When registering on the basis of distance, the shaft 3 is operated by a suitable mechanism controlled by the forward motion of the vehicle and the time mechanism is released.

The shaft 3 is secured to the sleeve 2 by a pin 4 so that operation of the shaft at all times will operate the sleeve 2 and consequently the disc 1.

Where time is a factor, motion is imparted to the shaft and usually at a greater rate, by means of the gear wheel 5 thereon. This gear wheel is operated by a suitable clock work. The wheel 5 has a sleeve 6 provided at its free end with teeth adapted to have clutching relation with corresponding teeth on the adjacent end of the sleeve 2, whereby the sleeve 2 is rotated and serves thus to transmit the increased speed to the disc 1.

The mileage transmission mechanism is released when the machine is operating on a time basis.

Mounted on the disc 1 and secured for rotation therewith is a star wheel 21 and a washer 23. The latter is attached to a disc 22, as shown.

The disc 1 is provided in its periphery with a notch *e* adapted to receive a pawl 24 mounted on an arm, indicated as a whole at 25, of the transmission mechanism to be later described. When the meter is started the disc 1 is rotated, but this will have no effect on the recording system until the pawl 24 drops into the notch *e*. The relation of the notch in the periphery of the disc 1 to the pawl may be regulated by shifting the disc in accordance with the standard distance or time used for computing the initial charge. When the meter stops, the disc 22 is turned to return the disc 1 and notch *e* to normal position.

When the notch is entered by the pawl the intermediate mechanism now to be described is brought into operation and the additional charge is recorded as the vehicle is used.

Assuming that the initial standard distance or time has been traveled, when the pawl 24 engages the notch *e*, a shoulder on the arm 25 drops automatically into engagement with one of the points of the star wheel 21. The arm 25 is secured to an arm 26 arranged to slide longitudinally on an arm 27. The arm 27 is pivoted at one end as at 28 and near its other end has an upstanding spacing member 29 which bears against a bar 30 pivoted at 31. The bar 30 at one end has a pawl 32. At a point in advance of the spacing member 29 is provided a pivoted counter pawl 152. Mounted on bar 30 is a pawl 30₁, extending downward while the lever 27 has a similar upwardly extending pawl 27.

The pawls 32 and 152 engage similar ratchet teeth 33 while the pawls 30₁ and 27₁ engage similar ratchet teeth 34 arranged contrary to the teeth 33. The teeth 33 and 34 form a double ratchet secured on a shaft 36. The operation of the shaft is accomplished by the engagement of the pawl 32 with the ratchet 33, and this rotation of shaft 36 turns the tariff indicating drums which are mounted on the shaft.

Assuming that the vehicle has covered a

standard distance or time corresponding to the initial charge as regulated by the relation of the notch *e* and pawl 24 and that the two latter elements are in engagement, 5 the shoulder on the arm 25 will drop into engagement with a tooth of the wheel 21 and the registering of the additional mileage or time will begin.

When the shoulder drops into the star 10 wheel the arm 26 is moved downwardly and the lever 27, spacing bar 29 and lever 30 are thus also swung downwardly. The pawl 30₁, on the lever 30 engages the ratchet 34 and when the shoulder is moving out of 15 the star wheel, and the said arms are raised, the pawl 27₁ engages the ratchet 34.

It will thus be seen that as the star wheel is rotated its engagement with the shoulder 20 on the lever 26 will serve to successively raise and lower the several levers. As the lever 26 is swung upwardly, it operates to swing the lever 27 and spacing bar 29 and the lever 30 bearing on the spacing bar, upwardly. The pawl 27₁ is brought into 25 engagement with the ratchet to prevent rotation thereof and the counter pawl 152 is similarly engaged with the ratchet. As the shoulder rides into one of the notches, the lever 26 is lowered; the pawl 27₁ is disengaged and at once the spacing bar being lowered, the lever 30 carrying the pawl 32 swings downwardly to allow the pawl 32 to snap into engagement with the ratchet and turn it the distance of one tooth. Immediately thereafter the pawl 30₁ is brought 35 into engagement with the ratchet and there can be no further rotation of the ratchet by reason of this engagement and the engagement of the pawl 152 except during the successive lowering of the levers by the star 40 wheel when the pawl 32 is snapped into engagement with the ratchet to turn it.

In this manner the slow continuous motion transmitted to the disc 1 is turned into 45 an abrupt or intermittent motion actuating the shaft carrying the tariff drums. This intermediate mechanism is efficient and dependable and it is to be noted that no springs or similar devices are employed. The provision of the pawls and the double ratchet mechanism serves to prevent any tampering 50 with the meter by the driver for the reason that the ratchet is only free to rotate in one direction at that instant when the pawl 32 snaps into the ratchet to turn it, since thereafter either the pawl 30₁ or the pawl 27₁ is selectively engaged with the ratchet to prevent rotation.

In order to set the device to zero as when 60 a trip is completed, the lever 146 is thrown outwardly on its pivot 147 by the cam 145. At its upper end, the lever 146 engages a bevelled portion 30' on the end of the lever 30 and will thus move this lever upwardly. 65 The releasing lever also engages a pin 148

on the pawl 32 and serves to draw the pawl 70 out of engagement with the ratchet. Thus by acting on the lever 30, the pawls 32 and 30₁ are removed from engagement with the ratchet; also the counter pawl may be disengaged when lever 30 is raised by the releasing member by reason of the spring 152₂, connected to the upper end 152₁ of said counter pawl. The releasing lever at the 75 same time acts on a pin 149 formed on the lever 26 and by means of lugs moves this lever to free the pawl 27₁ from the ratchet.

Thus all of the pawls are freed by a single 80 operation, and the shaft 36 carrying the ratchets and the tariff drum may be rotated to bring the drums back to normal position for another trip. This return movement is in the same direction as that of the shaft 85 36 when being turned by the ratchet mechanism.

It will be seen that I have provided a 90 simple construction and one which obviates the use of any springs. The transformation of the continuous movement into intermittent motion actuating the tariff drums is by 95 a compact arrangement, and there is no way in which the meter may be tampered with by a driver when in operation.

What I claim is:

1. In a taximeter, mechanism for transforming slow movement of distance-time actuated devices into abrupt movements upon a tariff drum, comprising in combination a shaft rotated by one of said devices, a star wheel secured to said shaft, an oscillating lever, a shoulder provided upon said oscillating lever cooperating with the teeth of said star wheel, a second oscillating lever, a pawl connected to one end of said second oscillating lever, a ratchet cooperating with said pawl mounted upon the shaft of the tariff drum, a spacing member provided upon said first lever whereby slowly to lift said second oscillating lever and return said pawl rearwardly, and a holding member movable with the first lever and restraining forward movement of the ratchet for a portion of the descending movement of the lever, so as to prevent an immediate descent of said second lever. 115

2. In a taximeter, mechanism for transforming slow movement of distance-time actuated devices into abrupt movements upon a tariff drum, comprising in combination a shaft rotated by one of said devices, 120 a star wheel secured to said shaft, an oscillating lever, a shoulder provided upon said oscillating lever cooperating with the teeth of said star wheel, a second oscillating lever, a pawl connected to one end of said second oscillating lever, a ratchet cooperating with said pawl mounted upon the shaft of the tariff drum, a spacing member provided upon said first lever whereby slowly to lift said second oscillating lever and return said 125

pawl rearwardly, a holding member movable with the first lever and restraining forward movement of the ratchet for a portion of the descending movement of the lever, so as to prevent an immediate descent of said second lever and to turn the tariff drum a predetermined distance, and to lock bolt cooperating with said ratchet after the start of the abrupt movements so as to prevent the tariff from turning further than a predetermined distance. ¹⁰

In testimony thereof I affix my signature.

CHARLES ALBERT DUBOIS.
